United States Patent

Des. 240,884
Patented Aug. 10, 1976

240,884

DISH OR SIMILAR ARTICLE

Frank J. Benes, Lancaster, Ohio, assignor to Anchor Hocking Corporation, Lancaster, Ohio

Original design application Sept. 13, 1973, Ser. No. 397,069. Divided and this application Feb. 10, 1975, Ser. No. 548,599

Term of patent 14 years

Int. Cl. D7—01

U.S. Cl. D7—20

Fig. 1.

Fig. 2.

FIG. 3.

FIG. 4.

FIG. 5.

FIG. 1 is a side elevational view of a dish or similar article showing my new design;

FIG. 2 is a bottom view thereof;

FIG. 3 is an end view thereof;

FIG. 4 is a top view thereof on a reduced scale;

FIG. 5 is a top view on a reduced scale of the dish of FIG. 1 showing the design modified to accommodate a candle or similar article; and

FIG. 6 is a fragmentary sectional view taken on line 6-6 of FIG. 5.

This is a division of design application Ser. No. 397,069 filed Sept. 13, 1973.

I claim:

The ornamental design for a dish or similar article, substantially as shown and described.
